STRETCHER JACK

James Madison Andrew, Elyria, Ohio

Application May 9, 1932. Serial No. 610,028

5 Claims. (Cl. 254—98)

This invention relates to telescope jacks in general and more particularly to stretcher jacks adapted to span a space between opposed walls or supports. Jacks of the kind described are self supporting, when rigidly clamped between their supports and may carry substantial weight. Adjustment of such jacks to proper length before their opposite ends contact with the opposed supporting walls is tiresome and necessitates use of heavy parts such as screw rods, ratchet rods and so forth, which materially increase weight and cost of these jacks. The general object of the present invention is to provide a stretcher jack with normally disengaged clutching means adapted to be engaged for interconnection of the telescoped parts of the jack with each other only when torsional strains or stresses are applied to the jack, thus permitting quick manual adjustment of the jack to proper size by longitudinal shifting of the telescoped parts with respect to each other and coupling of the telescoped parts by turning these parts with respect to each other and thru applying the necessary force to rigidly secure the jack between its supports. A further object of the invention is to provide a telescope stretcher jack with tilttable clutching means rotatably and axially shiftably interconnected with one of the telescoped elements and slidably and nonrotatably engaged with another of the telescoped elements to effect tilting and therewith clutching action of the clutching means by rotation and therewith axial shifting of one of said elements.

With these and other objects in view the invention consists in the construction and novel combination of parts fully described hereinafter, illustrated in the accompanying drawing, and pointed out in the claims appended hereto, it being understood that various changes in the form, proportion, size and minor details of construction within the scope of the claims, may be resorted to without departing from the spirit of the invention.

In the drawing forming a part hereof:

Figure 1 is a longitudinal section of an embodiment of the improved telescope stretcher jack;

Figure 2 is a view similar to Figure 1 with the clutch mechanism in engagement for coupling the telescoped parts of the jack;

Figure 3 is a longitudinal view of the jack extended to a length different from that shown in Figures 1 and 2;

Figure 4 is a sectional view on line 4—4 of Figure 1;

Figure 5 is a sectional view on line 5—5 of Figure 1; and

Figure 6 is a sectional view on line 6—6 of Figure 1.

In the embodiment of the invention as shown in the drawing, the telescope stretcher jack includes two sleeved tubings 1 and 2 axially shiftable with respect to each other, which may carry at their outer ends backing discs 4 and 5 respectively, padded by friction coverings 3. Backing disk 4 is rigidly secured to tubing 1, whereas disk 5 is pivotally engaged with tubing 2, carrying close to its outer end a disk 12, which is welded to tubing 2 and pivotally supports disk 5 by means of a loose rivet 13. A washer 14 is arranged between disk 12 and backing member 5 to decrease friction between said elements during rotation with respect to each other. Disk 4 centrally supports one end of a bar 6 which is preferably of rectangular cross section and at its other end fixed to a round disk 7, slidably arranged within tubing 2. Bar 6 axially extends through a screw and clutching mechanism C supported by and connected with tubing 2, which mechanism embodies a nut member 11, rigidly secured to tubing 2 by means of screws 11', a flanged screw member 8 interengaged with said nut 11, a stress bar 10 interengaged with the flange 8' of said screw member and a clutching disk 9 also interengaged with said stress bar. A circular axial passage 15 in screw member 8 permits rotation thereof with respect to rectangular bar 6, while a slot 16 in flange 8' of said screw member transmits slightest rotation of said screw member to stress bar 10 and therewith to clutch disk 9, slotted at 17 for engagement with said stress bar. An axial rectangular perforation 18 in clutch disk 9 fits bar 6 and permits axial shifting of said disk on said bar but prevents rotation between said disk and bar. Slots 19 and 20 in stress bar 10 interengage with slot 16 of flange 8' of screw member 8 and slot 17 of clutch disk 9 respectively to prevent axial shifting of stress bar 10 with respect to screw 8 and clutch disk 9. Slot 19 is rectangularly shaped to fit flange 8', while slot 20 embodies an inclined wall 21 and a straight wall 22 to permit tilting and straightening of said clutch disk during clutching and clutch releasing action of disk 9. Thus pushing of disk 9 by means of screw 8 induced by anticlockwise rotation of tubing 2 forces disk 9 to a tilted position in which the sharp edges of the rectangular perforation 18 thereof bite into rod 6, and securely couple disk 9 to rod 6, whereas pulling of disk 9 by means of screw 110.

8, induced by clockwise rotation of tubing 2 forces said disk to its straightened position, as straight wall 22 and the end wall 25 of tubing 2 engage such disk and straighten same up. In case disk 9 is in its straightened position the tubings 1 and 2 may readily and easily be shifted with respect to each other, without interference of the clutch mechanism see Figures 1 and 3 which show the shifting of said tubings, with respect 10 to each other when clutch disk 9 is in straightened position. Tilting of disk 9 is induced by rotation of tubing 2 in anticlockwise direction. Thus, when the tubing 1 is held stationary and the tubing 2 is rotated counter clockwise, the 15 stress bar 10 holds the head or flange 8' of screw 8 so that it cannot rotate with nut 11 and also causes a torsional force on clutch disk 9, thus affecting frictional locking on bar 6. As tubing 2 and therewith nut 11 rotates on screw 8 the inner open end 25 of tubing 2 moves away from clutch disk 9, and screw 8 through its flange 8', pushes longitudinally against stress bar 10 and forces said clutch disk out of its straightened 20 or vertical position into tilting and locking position on bar 6.

Sufficient force can then be exerted by continuing to rotate tubing 2, while holding tubing 1 stationary to apply enough pressure through pads 3, 3 so that the stretcher jack and its load 30 will be sustained between two opposite surfaces or walls.

Clockwise rotation of tubing 2, while holding tubing 1 stationary moves nut 11 along screw 8 toward the head or flange 8' of the screw 8 until 35 the open end 25 of the tubing 2 straightens coupling disk 9, so that no locking between rod 6 and clutch disk 9 occurs and that the tubings can be telescoped and adjusted for different distances if so desired.

Having thus described my invention what I claim is:

1. A stretcher jack, comprising a pair of telescoped tubes adapted to be shifted axially with respect to each other, means associated with one 45 of said tubes for forcing said tubes in opposite directions and automatically actuated coupling means between said latter means and the other of said tubes, said coupling means being engageable and disengageable with the latter of said tubes by torsional stresses applied to the first 50 of said tubes.

2. A stretcher jack, comprising a pair of tele-

scoped tubes adapted to be shifted axially with respect to each other, an extensible screw means including a screw nut rigidly secured to one of said tubes, a coupling means secured to and axially extending through the other of said tubes including a coupling disk slidably secured to said coupling means, and means between said screw means and said coupling disk adapted to transmit torsional stresses on said first tube to said coupling disk for tilting of said disk on said coupling means and interlocking of said disk and coupling means by such tilting.

3. A stretcher jack, comprising a pair of telescoped tubes adapted to be shifted axially with respect to each other, an extensible screw means secured to one of said tubes, including a nut attached to the inner wall of said tube and a headed screw engaged with said nut, a guide and coupling rod centrally within the other of said tubes and secured thereto, a coupling disk slidably and non-rotatably mounted upon said guide and coupling rod and a coupling stress bar for interconnecting the head of said screw with said coupling disk.

4. A stretcher jack according to claim 3, whereby said head of said screw, said coupling disk and said stress bar include cooperating slots for interengagement of said bar with said screw head and said coupling disk and whereby the one slot of said stress bar includes a straight 100 and an inclined side wall to straighten said coupling disk and to permit tilting thereof.

5. A stretcher jack comprising a pair of telescoped tubes adapted to be shifted axially with respect to each other, an extensible screw means 110 arranged within one of said tubes comprising a nut secured to the inner wall of said tube and a headed screw engaged with said nut, a guide and coupling rod centrally within the other of said tubes and secured thereto, a coupling disk 115 slidably and non-rotatably mounted upon said guide and coupling rod and a coupling stress bar for interconnecting the coupling disk and the head of said screw tiltably with respect to each other, said nut being so positioned and said coupling 120 disk, said headed screw and said stress bar being so dimensioned that at the end of the approach of the head of said screw to said nut, the end of the tube supporting said nut, engages said disk when in its straightened or vertical position with respect 125 to said guide and coupling rod.
